ARC FURNACE CONTROL

Lev A. Trofimov, Willoughby, Ohio

Application March 24, 1948, Serial No. 16,719

11 Claims. (Cl. 314—62)

1

This invention relates to apparatus for automatically controlling the arc standing between consumable electrodes, to maintain thereat predetermined quantitative electrical conditions.

The invention is applicable to the control of arcs as utilized in various arts such as lighting, welding, etc., but one of its most important uses is to control the arc of an electric arc furnace; and for the illustrative embodiment of the invention required by law upon application for a patent, I have chosen to illustrate and describe it herein as applied to that use.

In prior controls of this general class, one of the electrodes supporting the arc is mounted for movement toward and from the other electrode whereby the arc may be shortened or lengthened, to control it; and this general principle is utilized in the present invention; but otherwise the present invention departs from all prior practice so far as I am aware in at least the following elements of apparatus and mode of operation thereof.

A continuously running motor supplies power through a mechanical power transmission, to move the movable electrode with step-less movement, or to hold it at rest. The transmission supplies power from a rotary take-off, which in the preferred form of the invention responds to the joint effects of a pair of electromagnetic windings; and remains at rest when the effects of the windings balance or neutralize each other, and rotates in one direction or the other when the effect of one winding predominates over that of the other. The respective windings are energized commensurably with certain quantitative electrical conditions at the arc and their effects are balanced as aforesaid when predetermined conditions obtain at the arc; and upon deviation from said predetermined conditions become unbalanced and actuate the transmission to move the movable electrode to restore the predetermined conditions at the arc and to restore the balance at the transmission.

Among the advantages of the control over prior controls are that: the movement of the electrode to restore the predetermined conditions at the arc is initiated immediately upon deviation therefrom, because the power supplying motor is continuously running and no delay is introduced by the time required to start the motor; or stop and reverse the motor; and the rate of restoring the deviated condition is directly commensurable with the extent of the deviation; whereby the control or regulation is rendered exceedingly sensitive but at the same time "hunting" is ob-

viated. And this is true even in cases in which the electrode to be moved is of great mass and inertia and correspondingly large motor power is required to move it.

5 Furthermore, upon accidental interruption of the arc due to any cause, the transmission responds automatically to the resulting change of conditions at the arc, to immediately re-strike the arc and resume automatic control of it as before.

10 Upon failure of supply voltage to the control, the transmission responds to withdraw the movable electrode to a safety position and prevents it from dropping into the furnace or furnace charge as is true of some prior controls.

15 The invention may be practiced in various forms whereby the transmission may be made to respond to current in the arc, or to potential across the arc, or to both current and potential concurrently and therefore to watts in the arc; and by means of manual adjustments, the effectiveness of the response in either case may be adjusted to adapt a given control to a particular installation, and to adjustably vary, as 20 desired, the voltage at the arc, the length of the arc, the power factor of the electrode circuit, etc.

25 The objects of the invention are to provide an arc control having among others, the features referred to above.

30 The invention is fully disclosed in the following description of an embodiment thereof taken in connection with the accompanying drawing in which:

35 Fig. 1 is a diagrammatic view of an embodiment of the invention in a preferred form, illustrating an arc furnace and an electric system and apparatus for controlling the arc of the furnace, having the features of operation above referred to;

40 Figs. 2 and 3 are views similar to Fig. 1 but showing in simplified embodiments or modifications, some of the features of Fig. 1 and which in some installations may be sufficient for complete operation;

45 Fig. 4 is a view similar to Fig. 1 but simplified, illustrating certain elements energized with alternating current, which in Fig. 1 are energized with direct current.

50 Referring to the drawing, there is shown diagrammatically at 1 an arc furnace having a wall-enclosed furnace chamber 2. A stationary electric terminal 3 projects upwardly sealedly through the bottom chamber wall 4. An electrode 5 projects downwardly through an opening 6 in

the top chamber wall 7, being reciprocable in the opening.

Within the chamber 2 is shown in broken lines at 8-8 a quantity of metal pieces (or other charge) to be melted; and in solid line at 9 a quantity of molten metal; either of which in contact with the terminal 3 in the operation of the apparatus to be described, constitutes an electrode, between which and the electrode 5, an arc is drawn and maintained. Without any charge, an arc will be drawn and maintained between the electrode 5 and the terminal 3 as the other electrode for any chamber heating purpose.

A transformer 10 having a primary 11 connected to supply mains 12 by a switch 13, has a secondary 14 connected at one end by a main 15 to the terminal 3; and at its other end connected to the electrode 5 by a main 16 having a flexible portion 17 to allow for free reciprocatory movement of the electrode 5.

The weight of the electrode 5 may be artificially increased by a metal block 18, attached to it outside of and above the chamber 2.

A cable 19 is connected at one end to the electrode 5, preferably by attaching it to the block 18, extends upwardly therefrom, and passes over horizontally spaced pulleys 20-20, and thence downwardly to a drum 21 on which it is wound. Rotation of the drum in one direction winds up the cable and raises the electrode 5; and rotation in the other direction pays off cable and allows the weight of the electrode 5 and of the block 18 to lower the electrode by gravity.

A power transmission 22 for rotating the drum 21 will now be described. It comprises two differential gearings 23 and 24 preferably alike. The gearing 23 comprises a spider 25 rotatably supporting pinions 26-26 meshed with differential gears 27 and 28.

The gearing 24 comprises a spider 29 rotatably supporting pinions 30-30 meshed with differential gears 31 and 32.

The spiders 25 and 29 have toothed peripheries preferably of equal diameter, meshed together. A pinion 33, meshed with the spider 29, and driven by a continuously running motor 34 connected to supply mains 35 by a switch 36 continuously runs and drives the meshed spiders 25 and 29 in opposite directions.

The differential gears 27 and 31 are respectively connected to gears 37 and 38, preferably alike, both of which mesh with an intermediate gear 39 connected to the drum 21.

The differential gears 28 and 32 are respectively connected to shafts 40 and 41 to which are connected the rotors 42 and 43 of direct current dynamo-electric machines 44 and 45; having fields represented by field windings 46 and 47 respectively. The two machines 44 and 45 are preferably alike.

A local electric load circuit is provided comprising a wire 48 connecting adjacent brushes 49 and 50 of the machines 44 and 45; and a wire 51 connecting the opposite brushes 52-53.

The fields 46 and 47 are energized in a manner to be described later.

With this arrangement, and with like polarities for the fields 46 and 47 and assuming equal energization of the fields, the machines 44 and 45 will be driven as generators in opposite directions; their potentials will be equal and opposite; no current will flow in the local load circuit 48-51; and the rotors 42 and 43 will be driven at equal speeds and what torques are developed to drive the rotors will be equal and opposite.

This will cause the torques on differential gears 28 and 32 to be equal and opposite in direction, and cause the gears 27 and 31 to impress equal and opposite torques on the pinion 39 and its connected drum 21.

If, however, one field, say the field 47, be energized more strongly than the field 46, the machine 45 will continue to act as a generator; its potential will be greater than that of the machine 44; generated current will flow in the local circuit, to the wire 48, through the rotor 42 of the other machine 44, through the return wire 51; and the machine 44 will be driven thereby as a motor, in the same direction as before.

15 The electric load torque on the machine 45 now predominates and slows down its speed; the torques on differential gears 28 and 32 are in the same direction as before, but the gear 32 slows down and gear 31 which was at rest, starts to rotate, and through gears 38 and 39 applies torque to the gear-connected drum in the winding-up direction.

20 The machine 44 driven as a motor, rotates at an increased speed; the differential gear 28 increases in speed, and the differential gear 27 which was at rest starts to rotate in the reverse direction, and through the gears 37 and 39 applies torque to the gear connected drum again in the winding-up direction.

25 Thus the braking energy at the generator 45 is returned to the gearing system as motor power energy, by the motor 44.

30 If the field 46 were made stronger than the field 47 (instead of vice versa as above), then exactly the reverse action would take place and torque would be applied to the drum 21 in the paying off direction.

35 Whenever equality of the fields 46 and 47 is restored the torques applied to the drum again become equal and opposite.

40 As described, if the two units 44 and 45 are alike and have fields 46 and 47 alike and if the homologous parts of the gearings 23 and 24, etc., are alike, the torques applied to the drum 21 will be alike and in opposite directions when the fields 46 and 47 are equally energized. If under these conditions, there were no load torque on the drum 21, it would remain at rest; and if then the winding 47 were energized more strongly than the winding 46, the drum 21 would rotate in the winding up direction.

45 It will be apparent that there is always load torque on the drum 21 in the unwinding direction due to the weight of the electrode 5 and mass 18. To hold the drum 21 at rest therefore, torque must be applied to it in the winding-up direction to balance the load torque and this is done by energizing the field 47 more strongly than the field 46 by a suitable amount. A balanced condition 50 of the transmission and so-called balanced energization of the windings 46 and 47 is attained by providing this difference of energization of these windings.

55 There are several modes of field energization and control, manual and automatic, which will now be described.

60 At 54 is a double throw manual change-over switch, comprising four pivoted blades 55, 56, 57, and 58; and four upper contacts, 59, 60, 61, and 70 62, and two lower contacts 63 and 64 therefor.

65 When the blades 55 to 58 are in the lower position, the field 46 takes current from the outside brush 52 of its corresponding rotor 42, through the field 46, by wire 65 to blade 57, to contact 64, 75 by wire 66 through part 67 of the resistor 68 of

a potentiometer rheostat 68, through a manually movable contact 70 of the potentiometer, to wire 11, by way of wire 48 to the other brush 49.

Correspondingly, the field 47 takes current from brush 53 through the field 47, by wire 72 to blade 56 to contact 63 by wire 73 through the other part 74 of the potentiometer resistor 68, by contact 70 to wire 11, and by wire 48 to the other brush 50.

By adjusting the potentiometer contact 70, the fields 46 and 47 can be balanced as aforesaid or one made to predominate over the other.

Optionally, either field can be energized full strength, regardless of the potentiometer-set strength for the other field, by a double throw manual switch having a pivoted blade 75 connected to the wire 71 and two contacts 76-77 connected respectively to the wires 66 and 73. Throw of the switch blade 75 to the right short circuits the part 74 of the potentiometer resistor 68 and to the left short circuits the other part 67.

When these manual field strength controls are used, the fields are self-energized from their corresponding rotors as described; and by adjusting their relative strengths, the drum 21 can be caused to rotate in one direction or the other to raise or lower the electrode 5.

The automatic field control referred to comes into effect as follows, when the change-over switch 54 is thrown to the upper position.

The manual controls are rendered ineffective by being opened at the contacts 63-64.

The field 46 is connected by wires 65 and 78 to blades 57-58 and thence to contacts 61-62, and by wires 79-80 to the output points of a rectifier loop 81. The input wires 82-83 of this loop are connected through a double throw switch 84 to points 85 and 86 on the mains 16 and 15, that is, to the electrode 5 and the terminal 3. The field 46 during operation is thus subjected to potential commensurable with that across the arc formed between the electrodes. A manual rheostat 87 is placed in the line of wire 82 for adjustment to be referred to.

The field 47 is connected by wires 72 and 88 to the blades 55 and 56 and thence to contacts 59-60, and by wires 89-90 to the output points of a rectifier loop 91. The input wires 92-93 of this loop are connected through a double throw switch 94 to the secondary 95 of a current transformer 96 in the line of one of the mains, for example the main 16 as shown.

The field 47 during operation is thus subjected to potential commensurable with the current in the main 16 flowing in the arc. A manual rheostat 97 is placed in the line of the wire 92 for adjustment to be referred to.

Meters are preferably used in the operation of the apparatus. An ammeter 98 is placed in the line of one of the mains, for example the main 15 as shown to indicate arc current.

A volt meter 99 is connected across the points 85 and 86 by wires 100-101 to indicate potential across the arc.

A watt meter 102 has its volt terminals connected by wires 103-104 to the volt meter wires 100-101; and has its current terminals connected by wires 105-106 to the secondary 107 of a current transformer 108 in the line of one of the mains for example the main 16 as shown.

To start up the apparatus and set it in automatic operation, it will be assumed that the electrode 5 is above the lower electrode, namely the charge in the furnace chamber or the terminal 3 as the case may be.

The line switch 13 is closed, putting potential on the electrodes.

The change-over switch 54 is put in the lower position for manual operation.

The switch 36 is closed starting up the transmission motor 34.

The contact 70 of potentiometer 68 is now turned in the direction to equalize the fields 46 and 47 or to strengthen field 46 and weaken field 47. As described above, this will allow the drum 21 to be turned in the cable unwinding direction by gravity or will cause it to so turn and the electrode 5 will descend by gravity and engage the other electrode. Main current then flows in the engaged electrodes. Then the contact 70 is turned in the other direction to strengthen field 47 and weaken field 46 and the drum 21 reverses and winds up cable and withdraws the electrode 5 drawing an arc between the electrodes.

The potentiometer contact 70 is then adjusted until the winding up torque on the drum just balances the weight of the weighted electrode 5, and it is held stationary, or at least rises very slowly, maintaining the arc.

When a torque balance position is once determined in this manner for the potentiometer 68, the electrode 5 can be lowered and raised to strike an arc and then left in the balanced raised position, by first throwing the manual switch blade 75 to the left to give full strength to field 46 to lower the electrode; and then to the right to give full strength to the field 47 to raise the electrode; and then to the middle position to restore the fields to the potentiometer effected torque balance condition.

The arc having now been drawn and standing, with the electrode 5 substantially stationary, the change-over switch 54 is thrown to the upper position for automatic operation, which as described cuts off the manual controls, and energizes the field 46 from across-the-arc-potential, and energizes the field 47 from arc current derived potential. The rheostats 97 and 87 are now manually manipulated to adjust the fields 46 and 47 to establish a balance of torques on the drum 21 and desired conditions at the arc.

It is known that for a given arc furnace, a given kind and size of electrode, a given charge, etc., there is an optimum wattage in the arc, for stability of the arc and allowable power factor.

By means of the ammeter 98, volt meter 99, and wattmeter 102, the wattage in the arc, and the power factor can be observed and determined; and these optimum conditions can be brought about by adjusting the rheostats 87 and 97.

In the system as above described, the strength of the field 46 for any given voltage across the arc can be adjusted by the rheostat 87; and the strength of the field 47 for any given current in the arc can be adjusted by the rheostat 97.

The two fields can thus be given values such that by their joint action the electrode 5 is held stationary at a given length of arc.

If a longer arc is wanted, for example, the rheostat 97 can be operated to artificially strengthen the field 47. This will cause the electrode 5 to be raised, and the arc to be lengthened, until the consequent increasing potential across the arc and the decreasing current in the arc, bring the fields into torque balance again at a longer arc.

If a change of wattage is wanted, for example, the rheostats 87 and 97 can be jointly or severally manipulated while observing the wattmeter to adjust the arc to establish the desired wattage.

Once the desired optimum conditions are established by adjustment, they will be maintained automatically. Any burning away of the electrodes and lengthening of arc changes the relative field strengths because of the concurrent change in across-the-arc-potential and in arc current; and the drum 21 correspondingly is rotated to restore the wattage to the constant preselected value.

If due to any cause, the arc should become interrupted during operation, the current responsive field 47 would become de-energized upon cessation of current flow, but the across-the-arc-potential-responsive field 46 would still be energized. This would cause the drum 21 to be rotated to lower the electrode 5 until it engaged the other electrode. Thereupon heavy current would flow and field 47 would become strongly energized, but due to the absence of arc, the field 46 would be weak because the across-the-arc-potential would be weak. This would cause the drum 21 to be rotated to raise the electrode 5 and draw an arc, and then the automatic action would be resumed and regulate the arc to the present conditions.

Upon failure of supply voltage, or, upon shutting down the furnace, it is desirable to have the electrode pulled out of the furnace, or, at least retracted far from the charge.

Provision is made in the instant apparatus for this result. On the shaft 41 of the transmission is mounted a brake drum 109. A brake shoe 110 is normally held out of contact with it by a winding 111 energized from the line 35, when the switch 36 is closed. Upon failure of potential in the line 35 or upon opening the switch 36, the winding 111 will be de-energized and brake shoe 110 will engage the drum 109. This slows down the shaft 41, the same as when the field 47 is energized strongly, as described, and finally stops the shaft 41; and this causes the drum 21 to rotate to elevate the electrode 5, and this goes on throughout the time that the motor which has no braking action on it, continues to rotate by inertia.

As described hereinbefore, and in resume, when the movable electrode 5 is at rest for given arc conditions, its weight is supported by adjusted torque at the drum 21 in the winding up direction. When homologous parts of the transmission are identical or approximately so, the field 47 will at such times be stronger than the field 46; and this will result from unequal currents in the respective windings 47 and 46. Thereafter a relative strengthening of field 47 will raise the electrode 5, and a relative strengthening of the field 46 will lower it.

The constant wattage to which the apparatus regulates the arc, may be changed by means of taps 112 on the primary winding 11 of the transformer 10.

While I prefer as described, to energize the fields 46 and 47 respectively by variable potential commensurable with that across the arc, and by variable current commensurable with that in the arc, because of the constancy, sensitivity and non-hunting character of the regulation resulting therefrom; the scope of my invention comprehends modifications in which one or the other of the fields is energized with substantially constant current.

Fig. 1 has been made to include connections by which this optional mode of operation can be brought into action, to avoid the complications of more drawings. To optionally energize the

winding 46 at constant strength the double throw switch 84 is thrown from its lower illustrated position to an upper position, thereby disconnecting the wires 82-83 from the mains 16-15, and connecting them by wires 113-114 to a transformer secondary 115, energized from a transformer primary 119 connected to the mains 35.

As illustrative of the operation of this modification, the strengths of the fields 46 and 47 are adjusted as described, for the desired conditions at the arc and with a balance of the torques on the drum 21. As the electrode 5 is consumed and the current in the arc decreases, the resulting weakening of energization of field 47 and the constant energization of field 46 causes the field 47 to be relatively weaker, and this as described causes the drum 21 to rotate to lower the electrode 5 and restore the arc conditions.

To optionally energize the winding 47 at constant strength, the double throw switch 84 is returned to its illustrated position to energize the winding 46 at variable strength, and the double throw switch 94 is thrown from its illustrated lower position to an upper position thereby disconnecting the wires 92-93 from the current transformer 95 and connecting them by wires 116-117 to a transformer secondary 118.

As illustrative of the operation of this modification, the field strengths are again adjusted for balanced torques at the drum 21 for desired arc conditions. As the electrode 5 is consumed the potential across the arc rises, the resulting strengthening of the field 46 and the constant strength of field 47, unbalances the torques on the drum 21 and lowers the electrode 5 to restore the arc conditions.

In the modification of Fig. 2, a single differential gearing 120 is utilized, instead of the double differential 23-24 of Fig. 1, with corresponding simplification. A briefer description for this form will suffice, in view of the more complete description of Fig. 1.

A continuously running motor 121 drives the spider 122 which in turn drives the gears 123 and 124 which are connected respectively to the cable drum 21 and to a generator 125. The generator 125 has a local energy dissipating electric load circuit 126 containing adjustable resistance 126A; and has a field winding 127. When a double throw switch 128 is in the down position, the field 127 is connected to wires 129-130; and thence may be directly connected across the brushes of the generator 125 through a manual knife switch 131; or, through an adjustable resistor 132 when the switch 131 is open. When the switch 128 is in the upper position the field 127 is energized through a rectifier loop 133 from the secondary 134 of a current transformer in series with the electrode main 16, and adjusted by a manual rheostat 135.

The movable electrode 5 is suspended by a cable 19 wound on the drum 21, as in Fig. 1.

The electrode circuit 15-16 is energized by 65 a transformer 10 and its electrical quantities are indicated on instruments 98, 99, and 102 as in Fig. 1.

In this form, the weight of the electrode 5 and its overhauling weight 18 put torque on the drum 70 21 in the unwinding direction. Load on the generator, varied by variation of the strength of the field 127, applies variable torque on the drum in the winding up direction. The field 127 may be weakened or strengthened by the rheostat 135 75 to cause the drum to unwind or wind up cable

18, to lower or raise the electrode 5. The desired current in the arc may be established by making the field 127 more or less effective by adjusting the rheostat 135, until the torques balance. Thereafter changes in arc current will automatically unbalance the torques, and the electrode will be moved, and this will restore the current and the torque balance. For example, when the arc current decreases due to burning away of the electrode 5, the field 127 weakens, the torque applied to the drum 21 by generator 125 weakens, the electrode 5 descends, the current in the arc increases, the generator torque rises and a balance is again reached.

The electrode can be lowered and raised manually, with the switch 128 in the lower position, by operating the switch 131 to strike an arc; or can be moved gradually by operating the rheostat 132, when the switch 131 is open.

For an intermediate field strength, in a suitable adjusting range thereof, the electrode 5 and its weight 18 may be torque-balanced by adjusting the generator produced torque at the resistance 126A; and similarly, the length of the arc gap can be adjusted for any given field current adjustment by adjusting the resistance 126A.

In the event of accidental arc interruption, the field 127 becomes de-energized, the generator 125 rotates freely and little torque develops thereat, and correspondingly little torque is applied to the drum 21 in the winding up direction. The weight of the electrode, 5-18, overpowers the winding up torque, and the electrode descends. When it contacts the charge 8 or 9, current flows, field 127 is again energized, and the drum winds up cable and strikes an arc and the above described regulation is resumed.

If voltage on the motor mains 35 should fail, or if the switch 36 should be opened, the brake 110-111 (described for Fig. 1) sets and stops the rotation of gear 124, and so long as inertia of the motor rotor keeps it rotating, the drum 21 will be rotated in the winding up direction and withdraw the electrode 5. To keep the weight of the electrode 5-18 from overhauling the drum 21 and causing the electrode 5 to descend again, the driving connection between the spider 122 and motor driven pinion 33A may be a non-reversible worm and worm gear connection.

In the modification of Fig. 2 (as above described) an arc-current-responsive field winding 127, causes torque to be applied at the drum 21 in the winding up direction, to balance the weight of the electrode, 5-18.

In the modification of Fig. 3 (now to be described), torque at the drum 21 in the winding up direction overbalances the weight of the electrode 5-18, and an arc-voltage-responsive field winding causes torque to be applied to the drum 21 in the unwinding direction to balance the overbalancing torque.

In Fig. 3, as in Fig. 2, a single differential gearing 136 has its spider 137 continuously driven by a motor 138, and drives gears 139-140 connected respectively to a generator 141 and the drum 21. The cable 19 wound on the drum is connected at one end to the electrode 5 and at its other end to a weight 142. The weight 142 is sufficient to overbalance the weight of the electrode 5-18 and apply torque to the drum 21 in the winding up direction.

The field 143 for the generator 141 is controlled manually by the switches 128 and 131 and potentiometer 132 when energized from the generator 141 as described for Fig. 2; and in auto-

matic operation with the switch 128 in its upper position, is energized by way of wires 144-145 connected across the mains 15-16 and therefore across the arc, an adjusting rheostat 146, a rectifier loop 147, wires 148-149 and 150-151.

The generator 141 has a local load circuit resistance 152.

The arrangement will be seen to be substantially the same as that of Fig. 2 (and needs no further description); but here a balance is reached when the field 143 is energized sufficiently to cause the torque at the generator 141 to rise to the value at which the corresponding torque at the drum 21 tending to unwind cable 19 and lower the electrode is balanced by the weight 142.

If the potential across the arc increases due to consumption of the electrode 5, and lengthening of the arc, and energizes the field 143 more strongly, the drum 21 will wind up cable supporting the weight 142 and raise the weight, and unwind cable supporting the electrode 5-18 and allow the electrode 5 to move downwardly and restore the potential and the balance.

Upon failure of the arc, the potential across the electrodes will rise and strengthen the field 143 and cause the electrode 5 to be lowered into engagement with the charge 8 or 9; and current will at once flow, causing a reduction in potential which will weaken the field 143 and allow the weight 142 to raise the electrode 5 and draw an arc.

Upon failure of power in the motor mains 35 or upon cutting off the motor at the switch 36, the brake 110-111, as described hereinbefore, will set and stop the gear 139, and gear 140 and drum 21 will be driven in the unwinding direction and lower the electrode 5 so long as inertia in the rotor of the motor 138 persists; but as soon as the inertia is dissipated, the weight 142 will turn the drum 21 in the winding up direction and withdraw the electrode 5 as referred to.

In the foregoing embodiments of the invention, the drum is balanced or caused to turn in one direction or the other by the changing load developed in a direct current generator caused by a change of generator field energization supply, rectified from alternating current mains feeding the arc.

The modification of Fig. 4 is introduced to show that the generators may be of alternating current type and have alternating current fields.

Fig. 4 corresponds otherwise to Fig. 1, already described and therefore some of the manual controls have been omitted for simplification, but in view of their description for Fig. 1, those skilled in the art will know how to apply manual controls to Fig. 4.

Supply mains 12, transformer 10 with primary 11 and secondary 14, electrode mains 15-16, electrodes 5-3, winding drum 21, cable 19, and furnace 1 (indicated in broken line) are all reproduced from Fig. 1.

Two differential gearings 23 and 24 like those of Fig. 1 are connected to the drum 21 as in Fig. 1. Shafts 40-41 drive gears 153-154, and speed step up pinions 155-156 connected to the rotors 157-158 of generators 159-160.

These generators have the construction of three phase squirrel cage induction motors. The stator windings 161-162-163, which, when used as motor field windings, are connected each across one of the three supply phases, are here all connected in series, and across single phase

mains 164—165 for the generator 159, and 166—167 for the generator 160.

The mains 164—165 are connected to the secondary 168 of a transformer 169, the primary 170 of which is connected across the arc mains 15—16, the secondary 168 having taps and a movable arm 171 for adjusting the output potential.

The mains 166—167 are connected across the secondary 172 (adjustable by taps and a movable arm 173) of a current transformer 174 in the line of the main 16.

With the arrangement shown in Fig. 4 and as here described, when alternating current in, say, the mains 164—165 energize the field or stator of the generator 159, and the rotor 157 is driven at speeds above the synchronous speed corresponding to the frequency of the mains (insured by the speed step up at the gear and pinion 153—155), alternating current will be generated in the mains 164—165 and supplied back through them to the transformer 169 and thence to the electrode mains 15—16 and through the transformer 18 to the supply mains 12; this current constituting an electrical load on the generator 159; the mains 164—165 constituting mains for the exciting current of the stator of the generator and also load circuit mains therefrom; it being understood that there is a difference of phase between them caused by inherent conditions of the circuits. (Reference may be had if desired to a similar arrangement in my Patent 2,365,982, December 26, 1944.)

By changing the energization of the stator windings 161—162—163 the output load on the generator 159 and the torque to drive its rotor 157 will correspondingly be changed.

The generators 159 and 160 may be alike and the above description applies to both.

Load on the generator 160 tends to exert torque on the drum 21 to rotate it in the winding up direction and raise the electrode 5; and this occurs responsive to current in the arc and corresponding secondary voltage at the transformer 174, and field energization of the generator 160 and its current load, and the torque necessary to drive it.

Similarly, load on the generator 159, resulting from potential across the arc and on the secondary 168 of transformer 169, tends to exert torque on the drum 21 to rotate in the unwinding direction and allow the electrode 5 to descend.

The two torques are brought to a balance, the drum 21 remaining at rest and the potential and current of the arc at desired preselected values, by adjustment of the transformer output potentials at the movable contacts 171—173.

Thereafter predominance of load on one generator or the other by change of field strength occasioned by a change of said preselected values at the arc, will cause the drum 21 to rotate and reposition the electrode 5 to restore the balance and the preselected values.

From the foregoing description, it will be apparent to those skilled in the art that the invention is not limited to details of construction; but admits of a variety of embodiments, and modifications thereof and changes therein; and my invention is comprehensive of all such changes and modifications that come within the scope of the appended claims.

I claim:

1. In an apparatus for adjustably moving a consumable arc-supporting electrode to maintain at a predetermined value an electrical quantity at the arc that tends to vary; a differential

power transmission comprising a rotary power output element and an electric generator having an electric load circuit, and a field winding; the transmission constructed to receive power from a continuously running motor and apply equal torques differentially to the output element and to the generator; and to respond to variations of energization of the field winding to vary the torque of the generator to correspondingly vary the torque of the output element; means biasing the electrode to move it in one direction; means communicating torque of the output element to the electrode in opposition to its bias; circuit means energizing the field winding proportionally to an electrical quantity at the arc, to cause the output element to effect movement of the electrode to restore the electrical quantity to a predetermined value upon deviation of the quantity from said value.

2. In an apparatus for adjustably moving a consumable arc-supporting electrode to maintain the current in the arc at a predetermined value as it tends to vary; a differential power transmission comprising a rotary power output element and an electric generator having an electric load circuit, and a field winding; the transmission constructed to receive power from a continuously running motor and apply equal torques differentially to the output element and to the generator; and to respond to variations of energization of the field winding to correspondingly vary the torque of the generator and of the output element; means biasing the electrode to move in one direction to tend to change the current; means communicating torque of the output element to the electrode in opposition to its bias; circuit means energizing the field winding proportionally to the current in the arc to cause the output element to effect movement of the electrode to restore the current to a predetermined value upon deviation of the current from said value.

3. In an apparatus for adjustably moving a consumable arc-supporting electrode to maintain the voltage across the arc at a predetermined value as it tends to vary; a differential power transmission comprising a rotary power output element and an electric generator having an electric load circuit, and a field winding; the transmission constructed to receive power from a continuously running motor and apply equal torques differentially to the output element and to the generator; and to respond to variations of energization of the field winding to correspondingly vary the torque of the generator and of the output element; means biasing the electrode to move in one direction to tend to change the voltage; means communicating torque of the output element to the electrode in opposition to its bias; circuit means energizing the field winding proportionally to the voltage across the arc, to cause the output element to effect movement of the electrode to restore the voltage to a predetermined value upon deviation of the voltage from said value.

4. In an apparatus for adjustably moving a consumable arc-supporting electrode to maintain the current in the arc and the voltage across it at predetermined values as they tend to vary; a power transmission comprising a pair of rotary torque developing means and a rotary output element and differential gearing constructed to be driven by the torque of a continuously running motor and differentially connected to the output element and to the two torque developing means

respectively; a pair of electric controlling windings for the respective torque developing means relative energization of which varies relatively the torques developed by the two torque developing means and in consequence the direction and amount of resultant torque at the output element; means including means to apply torque of the output element to the electrode to effect movement of it; circuit means energizing the respective windings proportionally to current in the arc and voltage across it, respectively, to cause the torque on the output element to effect movement of the electrode to restore the current and voltage to predetermined values, upon deviation thereof from said values.

5. In an apparatus for adjustably moving a consumable arc-supporting electrode to maintain the current in the arc and the voltage across it at predetermined values as they tend to vary; a power transmission comprising a pair of rotary torque developing means and a rotary output element and differential gearing constructed to be driven by the torque of a continuously running motor and differentially connected to the output element and to the two torque developing means; a pair of electric controlling windings for the respective torque developing means relative energization of which varies relatively the torques developed by the two torque developing means and in consequence the direction and amount of resultant torque at the output element; means including means to apply torque of the output element to the electrode to effect movement of it; circuit means energizing one winding at values proportional to current in the arc and the other winding at a constant value, to cause the effects of the windings to be balanced at a predetermined value of current and to cause the effects to be unbalanced and the electrode to be moved to restore the current to said value upon deviation therefrom.

6. In an apparatus for adjustably moving a consumable arc-supporting electrode to maintain the current in the arc and the voltage across it at predetermined values as they tend to vary; a power transmission comprising a pair of rotary torque developing means and a rotary output element and differential gearing constructed to be driven by the torque of a continuously running motor and differentially connected to the output element and to the two torque developing means; a pair of electric controlling windings for the respective torque developing means relative energization of which varies relatively the torques developed by the two torque developing means and in consequence the direction and amount of resultant torque at the output element; means including means to apply torque of the output element to the electrode to effect movement of it; circuit means energizing one winding at values proportional to voltage across the arc and the other winding at a constant value, to cause the effects of the windings to be balanced at a predetermined value of voltage and to cause the effects to be unbalanced and the electrode to be moved to restore the voltage to said value upon deviation therefrom.

7. In an apparatus for adjustably moving a consumable arc supporting electrode to maintain the current in the arc and the voltage across it at predetermined values, as they tend to vary; a power transmission comprising a pair of load developing electric generators and a rotary output element, and differential gearing constructed to be driven by the torque of a continuously run-

ning motor and to differentially apply torque to the output element and to the two generators; a pair of controlling windings relative energization of which varies relatively the developed load torque of the generators and in consequence the direction and amount of resultant torque at the output element; means including means to apply torque of the output element to the electrode to effect movement of it; circuit means energizing the respective windings proportionally to current in the arc and voltage across it, respectively, to cause the torque on the output element to effect movement of the electrode to restore the current and voltage to predetermined values, upon deviation thereof from said values.

8. In an apparatus for adjustably moving a consumable arc supporting electrode to maintain the current in the arc and the voltage across it at predetermined values as they tend to vary; a power transmission comprising a pair of electric generators and a rotary output element and differential gearing constructed to be driven by the torque of a continuously running motor and to differentially apply torque to the output element and to the two generators; a common load circuit for the generators, a pair of field windings for the respective generators, relative unbalanced energization of which, rendering one winding more effective than the other, causes one or the other of the generators to generate load current in the common load circuit and drive the other generator as a motor and develop braking torque, and as a consequence to determine the direction of torque at the output element; means including means to apply torque of the output element to the electrode to effect movement of it; circuit means for energizing the respective field windings proportionally to current in the arc and voltage across it, respectively and for balancing their energizations when the current and voltage are at said predetermined values, and when their energizations are unbalanced, to cause the torque at the output element to effect movement of the electrode in the direction to restore the current and voltage to said predetermined values, upon deviation thereof from said values.

9. In an apparatus for adjustably moving a consumable arc supporting electrode to maintain the current in the arc at a predetermined value as it tends to vary; a power transmission comprising a pair of electric generators and a rotary output element and differential gearing constructed to be driven by the torque of a continuously running motor and to differentially apply torque to the output element and to the two generators; a common load circuit for the generators, a pair of field windings for the respective generators, relative unbalanced energization of which, rendering one winding more effective than the other, causes one or the other of the generators to generate load current in the common load circuit and drive the other generator as a motor and develop braking torque, and as a consequence to determine the direction of torque at the output element; means including means to apply torque of the output element to the electrode to effect movement of it; circuit means for energizing one field winding proportionally to current in the arc and the other at constant energization; and for balancing their energizations when the current is at said predetermined value; and, when their energizations are unbalanced, to cause the torque at the output element to effect movement of the electrode in the direction to restore the current to said

predetermined value upon deviation thereof from said value.

10. In an apparatus for adjustably moving a consumable arc supporting electrode to maintain the voltage across the arc at a predetermined value as it tends to vary; a power transmission comprising a pair of electric generators and a rotary output element and differential gearing constructed to be driven by the torque of a continuously running motor and to differentially apply torque to the output element and to the two generators; a common load circuit for the generators, a pair of field windings for the respective generators, relative unbalanced energization of which, rendering one winding more effective than the other, causes one or the other of the generators to generate load current in the common load circuit and drive the other generator as a motor and develop braking torque, and as a consequence to determine the direction of torque at the output element; means including means to apply torque of the output element to the electrode to effect movement of it; circuit means for energizing one field winding proportionally to the voltage across the arc and for balancing their energizations when the voltage is at said predetermined value, and when their energizations are unbalanced, to cause the torque at the output element to effect movement of the electrode in the direction to restore the voltage to said predetermined value, upon deviation thereof from said value.

11. In an apparatus for adjustably moving a consumable arc supporting electrode to maintain at a predetermined value an electrical quantity at the arc that tends to vary; a differential power

transmission comprising a rotary output element, and a rotary torque developer comprising a winding; the transmission constructed to receive torque from a continuously running motor and apply equal torques differentially to the output element and to the torque developer independently of speed of the motor; and constructed to respond to variations of energization of the winding to vary the torque developed by the torque developer, to correspondingly vary the torque of the output element; means biasing the electrode to move it in one direction; means communicating torque of the output element to the electrode in opposition to its bias; circuit means energizing the winding proportionally to an electrical quantity at the arc, to cause the output element to effect movement of the electrode to restore the electrical quantity to a predetermined value upon deviation of the quantity from said value.
